UNITED STATES PATENT OFFICE.

THOMAS STRAHAN SHENSTON, OF BRANTFORD, ONTARIO, CANADA.

CAR-BRAKE.

SPECIFICATION forming part of Letters Patent No. 426,836, dated April 22, 1890.

Application filed February 20, 1890. Serial No. 341,192. (No model.)

To all whom it may concern:

Be it known that I, THOMAS STRAHAN SHENSTON, a subject of the Queen of Great Britain, and a resident of Brantford, in the Province 5 of Ontario, Dominion of Canada, have invented certain new and useful Improvements in Car-Brakes, of which the following is a specification.

This invention has reference to improvements in car-brakes in which a brake-shoe is forced into contact with the tread of a wheel by means of screws acting directly on such brake-shoes and operated from some convenient point in the car by means of suitable 15 flexible connections, and in which the application and maintenance of great force upon the brake-shoes are insured without subjecting the intermediate connections to continued strain in order to effect such result.

20 The improvement therefore consists, essentially, in mounting a shaft having its ends threaded in opposite directions, so as to extend longitudinally between the treads of each pair of wheels on each side of the car-truck, 25 brake-shoes mounted upon such threaded ends of each shaft, and chain-gear extending from such shafts to some suitable point on the car from which the chain may be operated to rotate the shafts simultaneously, and thus 30 carry the brake-shoes into or out of contact with the treads of the truck-wheels, all as will hereinafter more fully appear.

In the accompanying drawings I have represented a preferred construction embodying 35 my improvements; and it will be understood that I am by no means limited by such identical structures, as they may be variously modified without departing from the principles of the invention.

40 In the drawings, Figure 1 is a side elevation of the chain gearing and connections, together with the two shafts operated thereby. Fig. 2 is a plan view of the same with the brake-wheel and guide-pulley shafts in section; and 45 Fig. 3 is an elevation, partly in section, of the truck with the brake-shoes and operating-shaft applied.

Referring now to the drawings, there are shown two shafts 1 2, each of which is reduced in diameter at its ends and there provided with right and left handed screw-threads, respectively, as shown at 3. Cen-

trally upon each shaft there is mounted a sprocket-wheel 4, and these shafts are mounted in hangers 5, depending from opposite sides 55 of a truck-frame 6. The hangers are so located that each shaft will extend longitudinally between each pair of truck-wheels 7 of the truck, with the screw-threaded ends 3 projecting beyond the hangers and the sprocket- 60 wheel 4 confined between the same.

Upon the screw-threaded ends 3 of the shafts 1 and 2 are mounted brake-shoes 8, each shoe being provided with a boss 9, in which is formed a nut for the respective 65 screw-threaded end of the shaft, and the bearing-faces of these brake-shoes are placed as close as practicable to the treads of the wheels, so that but a limited rotation of the shaft is necessary in order to force the brake-shoe into 70 firm contact with the tread of the wheel.

It will be understood that the brake-shoes are held against rotation either by engaging the flanges of the wheels or by suitable guides, and that the right and left hand screw-threads 75 on the shaft will tend to move the brake-shoes simultaneously in opposite directions, the shaft itself being held against longitudinal movement by the brackets 5 engaging the sides of the sprocket-wheel 4. It will likewise 80 be observed that the screw-threaded shaft admits of the application of great power to the brake-shoes to force them strongly against the treads of the wheels, and that when the brakes are so applied they will remain in such position until the shaft is positively rotated in the opposite direction, thus obviating the use of detents and all strain on the connections employed for rotating the shaft.

The brakes are operated from a suitable 90 shaft 10, extending through the car-platform 11, and carrying on its upper end a brake-wheel 12, and below the platform 11 a sprocket-wheel 13. Around each sprocket-wheel 4 there extends a section 14 of sprocket-chain, 95 these chains being connected together on one side by a length 15 of ordinary link-chain and on the other side by similar chains 16 17, extending to the respective ends of a sprocket-chain section 18, passing around the sprocket-wheel 13 on the brake-wheel shaft 10, the said chains 16 and 17 also passing around a guide-pulley 19, mounted upon a shaft 20, having suitable bearings below the car-plat- 100

form 11 at some convenient point between the shafts 1 and 2, so that the direction of the chains 16 and 17 may be changed, since, as will be observed, the sprocket-wheel 13 on the shaft 10 is necessarily located at some distance from the car-truck, in order to be conveniently placed on the car-platform, and the sprocket-wheel 13 rotates in a horizontal plane, while the sprocket-wheels 4 rotate in a vertical plane. If now the brake-wheel 12 be manipulated to rotate the shaft 10 and sprocket-wheel 13 in the direction of the arrow, Fig. 2, the chain 16 will be drawn toward the said sprocket-wheel 13, while the chain 15 will be free to move away from it. This movement of the chain 16 will cause it to carry the sprocket-chain 14 connected to it in a direction to rotate the shaft 2 in such manner that the brake-shoes carried thereby will be forced toward and into contact with the wheel-treads; and since the other sprocket-chain 14 is connected to the first-mentioned sprocket-chain 14 by the chain 15 it will participate in the movement described and rotate the sprocket-wheel 4 of the shaft 1. At the same time this movement will take up the slack of the chain 17. The threaded ends of the shaft 1 are so arranged that when moved in the manner described they will force the brake-shoes against the treads of the respective wheels simultaneously with the like movements caused by the rotation of the shaft 2. Thus it will be seen that when the brake-wheel is manipulated in one direction the brake-shoes on each side of the truck are simultaneously forced into contact with the wheel-treads, and that a comparatively small amount of power applied at the brake-wheel will be sufficient to apply the brakes with great force, and that, as before stated, no detents are necessary in order to maintain the braking action, nor is it necessary that a continuous force be applied through the intermediate connections.

In order to loosen the brakes, the brake-wheel is rotated in the opposite direction, when the chain will operate to rotate the

screws to draw the brake-shoes away from the wheels.

Since the sprocket-chain is of much more costly construction than an ordinary link-chain, and since the chain-connections have but a limited movement, only so much sprocket-chain is used as is necessitated by the size and number of the sprocket-wheels. 55

Having now fully described my invention, I claim and desire to secure by Letters Patent—

1. In a car-brake, the combination of a pair of brake-shoes on each side of the truck, and right and left handed screw-shafts, one for each pair of brake-shoes, for simultaneously operating the same, with a brake-wheel mounted on the platform of the car, and chain-gearing connecting the brake-wheel 65 with the screw-shafts, substantially as described.

2. In a car-brake, the combination of a pair of brake-shoes on each side of the truck, right and left handed screw-shafts, one for each pair of brake-shoes, for simultaneously operating the same, and a sprocket-wheel on each shaft, with a brake-wheel mounted on the platform of the car, a sprocket-wheel operated by the brake-wheel, and chain-connections therefrom to the sprocket-wheels on the screw-shafts, substantially as described. 70

3. In a car-brake, the combination of a pair of brake-shoes on each side of the truck, and a right and left handed screw-shaft and sprocket-wheel thereon for each pair of brake-shoes, with a brake-wheel and sprocket-wheel operated thereby, and chain-gearing connecting the brake-wheel and screw-shafts for operating the latter simultaneously, and embracing sections of sprocket-chain at the said sprocket-wheels, substantially as described. 85

In testimony whereof I have signed my name to this specification in the presence of two subscribing witnesses.

THOMAS STRAHAN SHENSTON.
